CIGARETTE LIGHTER

Irving Florman, New York, N. Y.

Application June 27, 1934, Serial No. 732,696

4 Claims. (Cl. 67—7.1)

My invention relates to a cigarette lighter and more particularly to a scratch lighter of the flameless type.

Various types of material are known which can be ignited by a spark and which when so ignited will smoulder and become sufficiently hot to ignite a cigarette without actually breaking into flame. Naturally such material does not, as does a wick, last for a practically indefinite period, but must be renewed as the smouldering action actually burns the fiber and destroys the same. A large body of such material is often used, but this body must be frequently shifted so as to bring a fresh portion into position adjacent the 10 sparking member.

The object of the present invention is to provide a lighter of this type in which a single member serves both to produce the sparks and to move and adjust the ignitable material whenever 20 necessary.

A further object of the invention is to provide a simple, compact and useful lighter of this type which can be manufactured inexpensively and which is efficient in its operation.

25 Further objects and advantages of the invention will appear more fully from the following description, when taken in conjunction with the accompanying drawing which forms a part thereof.

30 In the drawing:

Fig. 1 is a side view of the lighter in closed position.

Fig. 2 is a similar view, partly in section, showing the parts in the position which they occupy 35 during operation.

Fig. 3 is a vertical cross section through the lighter.

Fig. 4 is a cross section on the line 4—4 of Fig. 3.

40 Fig. 5 is a bottom plan view of the cover member.

The lighter comprises a body or casing 2 preferably relatively thin and flat, and divided into two compartments 4 and 6 by a wall 8. This body may be cast in one piece of some plastic 45 material such as artificial resin. In the larger chamber 6 is arranged a mass 10 of a combustible material of any well known type which smoulders without actually breaking into flame. The term 50 "smouldering material" as used in this specification and claims is intended to define such a composition, which may for example be cotton or other fibrous substance suitably impregnated to give the desired result.

55 The upper top of the casing 2 is open, but may

be closed by a cover 12, which is provided around at least a portion of its periphery with a flange 14 which fits inside the open upper end of the casing 2. The cover is provided with a handle 16 which may be in the form of an ornament if desired. This cover will close the casing and when in position will serve to extinguish the smouldering material by excluding air therefrom.

The smouldering material is ignited by sparks produced by the action of a steel member on a 10 flint strip. The steel may for example constitute a striking element 18 embedded in the top of the wall 8 and extending somewhat above the upper edge of casing 2 into a recess 20 in the cover 12. This member preferably is provided 15 with a sharp edge at its top as is usual in strikers. The flint strip 22 is carried by a stem or rod 24 extending downwardly from the cover 12 and, when the cover is in position, extending into the recess or chamber 4. The lower end of the flint 20 strip and stem are preferably pointed as at 26. As will be noted, the cover is generally flat, and the stem 24 extends at right angles thereto.

In using the lighter, the cover is removed by the handle 16 and moved to the position shown in 25 Fig. 2. The flint strip is then drawn rapidly over the steel striker member 18, producing sparks which will ignite the material 10. When this is ignited a cigarette may be placed against it and will be lit.

If the upper portion of the smouldering material is burned away during use, it is necessary to bring fresh material to the top. The stem 24 may very conveniently be used for this purpose, and, as it is pointed, it is particularly advantageous 35 in rearranging or shifting the position of the smouldering material within its chamber.

When the cigarette has been lit, the cover is replaced and will immediately extinguish the smouldering material.

While I have described herein one embodiment of my invention, I wish it to be understood that I do not intend to limit myself thereby except within the scope of the appended claims.

I claim:

1. A lighter comprising a casing open at its top, smouldering material within said casing accessible for contact by a cigarette through the open top thereof, a striking member carried by said casing adjacent said smouldering material, 50 a cover for closing the open top of said casing and extinguishing said smouldering material, and a flint strip holder extending downwardly from said cover and at an angle thereto, said strip holder being adapted to penetrate into the ma- 55

terial through the open top of the casing to rearrange the smouldering material.

- 5 2. A cigarette lighter comprising a casing open at its top, smouldering material within said casing accessible for contact by a cigarette through the open top thereof, a striking member carried by said casing adjacent said smouldering material and extending above the upper edge of the casing, a cover for closing the open top of said casing and extinguishing the smouldering material, said cover having a recess therein to receive said striking member, and a flint strip holder carried by said cover and extending downwardly below said cover, said flint strip holder 10 cooperating with said striking element to produce sparks and further being adapted to penetrate into the material through the open top of the casing for the rearrangement of said smouldering material.
- 15 20 3. A lighter comprising a casing open at its top, said casing having a wall dividing the same into two compartments, smouldering material in one of said compartments accessible for contact with a cigarette through the open top thereof, a striking element mounted at the upper edge of said wall, a cover closing both compartments of said casing, a member extending downwardly from said cover and arranged to enter the other

of said compartments, and a flint strip carried by said member and cooperating with said striking element to ignite said smouldering material, said member likewise being adapted to penetrate into the material through the open top of the 5 casing for the rearrangement of said smouldering material.

4. A lighter comprising a casing open at its top, said casing having a wall dividing the same into two compartments, smouldering material in 10 one of said compartments accessible for contact with a cigarette through the open top thereof, a striking element mounted at the upper edge of said wall and extending above the upper edge of said casing, a cover closing both compartments 15 of said casing, said cover having a recess therein arranged to receive the upper end of said striking element, said cover being generally flat, a member extending downwardly from said cover at right angles thereto and arranged to enter the other 20 other of said compartments, and a flint strip carried by said member and cooperating with said striking element to ignite said smouldering material, said member likewise being adapted to penetrate into the material through the open 25 top of the casing for the rearrangement of said smouldering material.

IRVING FLORMAN.
